UNITED STATES PATENT OFFICE.

JOHN B. WILLIAMSON AND HARRY L. MEANS, OF LOUISVILLE, KENTUCKY;
SAID WILLIAMSON ASSIGNOR TO SAID MEANS.

MUSIC-SHEET TURNER.

SPECIFICATION forming part of Letters Patent No. 660,980, dated October 30, 1900.

Application filed December 13, 1899. Serial No. 740,213. (No model.)

To all whom it may concern:

Be it known that we, JOHN B. WILLIAMSON and HARRY L. MEANS, residents of Louisville, in the county of Jefferson and State of Kentucky, have invented certain new and useful Improvements in Music-Sheet Turners; and we do hereby declare the following to be a full, clear, and exact description of the invention, such as will enable others skilled in the art to which it appertains to make and use the same.

Our invention relates to an improvement in music-sheet turners, the object of the invention being to provide a device of the above-mentioned character with improved means for turning the sheets or pages of music and also improved means for retaining the sheets or pages in proper position.

With this object in view the invention consists in certain novel features of construction and combination and arrangements of parts, as will be more fully hereinafter described, and pointed out in the claims.

In the accompanying drawings, Figures 1 and 4 are views illustrating our improvements. Fig. 2 is a side view of the catch-operating mechanism, and Figs. 3, 5, and 6 are enlarged views of details of construction.

A represents an inverted-T-shaped frame or support, comprising the vertical member 1 and the horizontal member 2 at the lower end thereof and disposed at right angles thereto. A casing 3 is secured to the horizontal member 2 of the frame or support A, and a lug 4 is secured to the bottom of the casing 3 and is bent at its lower end to form an ear 5, having a screw-threaded hole therein for the passage of a set-screw 6, carrying a swiveled plate 7 at its free end to clamp the outwardly-projecting member of a music-rest (not shown) between said plate 7 and the base of the casing 3 to secure the sheet-turner in proper position. The casing and clamp are provided with a covering of felt or other soft material to prevent scratching. A series of brackets 7^a are secured to the vertical member 1 and are spaced a suitable distance apart and are provided with alined openings for the passage of tubular shafts 9, disposed one within the other and of varying lengths, as many of said shafts being provided according to the number of swinging arms 10 that may be employed, each of the latter be-

ing secured to a separate shaft and each shaft provided with a spring 11, disposed around the shaft and secured thereto at one end and at its other end to a bracket 7^a.

The casing 3 is provided at one side of its center with a vertically-disposed plate 12, having a flange 13 at one side secured to the member 2, and the upper end of said plate 12 projects through a slot in the top of the casing 3 and is bent over to form a flange 14 at the top of the casing and a narrow flange 15 at the front edge thereof. The plate 12 is provided on one side with an eye 16, which, together with a hole in the flange 14, forms a guide or bearing for a bolt 17, to which latter, at its lower end, is connected one end of a spring 18, which is coiled between its ends around a screw 19, secured to the member 2 and at its free end disposed against the bottom of the casing 3. The bolt 17 is provided on its outer face with a series of ratchet-teeth adapted to be engaged by a spring-pressed dog 19, pivoted to a push-rod 20, projecting outside the casing 3 and provided on its outer end with a button or knob 21. The dog 19 is adapted to force the bolt 17 step by step in a downward direction, and a spring-pressed dog 22, pivotally connected to the plate 12, is adapted to engage the teeth on the bolt and hold the same against upward movement. Both of said dogs 19 and 22 are provided with outwardly-projecting pins 23, adapted to be engaged by a plate 24 to force said dogs out of engagement with the bolt and permit the latter to spring to its highest position. The plate 24 is provided on the lower end of a lever 25, pivoted between its ends to the plate 12 and projecting out through the flange 14 and adapted to be engaged by the swinging arms 10 when they are thrown to the right to force the plate 24 in engagement with the dogs and permit the bolt 17 to spring upward and hold the arms 10 in proper position. A spring 26, coiled between its ends around a screw 27, secured to the plate 12, is connected at one end to the inner end of the push-rod 20 and adapted to press the same outward, and the other end of said spring is disposed against a pin 27 on the lower end of lever 25 to hold the lever in its normal position.

The operation of this portion of our invention is as follows: When the pages of a sheet of music are to be placed in position, the

sheets or pages are inserted at their lower ends in the spring-clamps *a* at the ends of the arms 10, and said arms are moved over to the right until they strike the lever 25, and when 5 said lever is pressed inward the plate 24 will force the dogs 19 and 22 out of engagement with the bolt 17 and permit the latter to spring upward and hold the arms 10 in the position to which they are moved. When it is desired 10 to turn a page or sheet, the push-rod 20 is forced inward, which operation will force the dog 19 (which is disposed against a tooth on the bolt) downward, and hence push the bolt downward a sufficient distance to release one 15 arm 10 and permit the same to swing to the left, carrying a sheet or page with it. The dog 22 now engages the next tooth on the bolt and holds the same in its adjusted position. The push-rod 20 is operated as above de- 20 scribed until all of the arms 10 have been released and swung to the left, thus turning all of the sheets or pages of music.

A casing 28 is secured on the vertical member 1 of the bracket A and is adapted to in- 25 close the brackets 7^a, shafts 9, and springs 11. The front face of the casing 28 is pro- 30 vided with two parallel jaws 29 and 30, the former stationary and secured to the casing and the latter movable and normally pressed 35 away from the movable jaw by springs 31, as shown. A bar 32 is secured to one side of the casing 28 and is provided on its outer end with a pin 32^a, on which a cam-lever 33 is ful- 40 crumed. The cam-lever 33 is adapted to en- 35 gage the movable jaw 30 and clamp the edge of a sheet of music between said jaws. A lug 34^a is provided on the movable jaw 30 and is disposed between the inner face of the cam-lever 33 and the casing to prevent the 45 movable jaw from outward displacement.

A plate 34 is secured to the lower end of the casing 28 and is provided with an out- 50 wardly-projecting portion having an oval-shaped opening 35 therein, and a plate 36 is secured to the upper end of the casing 28 and is provided on opposite sides with perforated ears 37. Similar ears 38 are provided on a movable plate 39, and pivot-pins connect the ears 37 and 38, and the outer end of said mov- 55 able plate is provided with an oval-shaped opening 41 in alignment with the opening 35 in plate 34 for the reception of a rod 42, having a recess 43 at each end to bear against the edge of the plates, and it will be seen that 60 when it is desired to hold a book on the sheet-turner it is simply necessary to insert the rod 42 in the binding of the book, then place the lower end of the rod in the hole in the lower plate 34, and then adjust the plate 39 to re- 65 ceive the upper end of the rod in the opening 41, and the thickness of the binding will hold the recessed portions of the rod in the extreme outer or contracted portion of the open- 65 ings 35 and 41, and hence prevent accidental displacement of said rod.

Instead of mounting the telescoping shafts 9, brackets 7^a, and springs 11 in the casing 28, we may mount the same in the casing 3, and instead of employing coiled springs for operating said shafts we might employ flat 70 springs or other means for throwing the arms from right to left.

Various other slight changes might be re- 75 sorted to in the general form and arrangement of the several parts described without departing from the spirit and scope of our invention, and hence we would have it understood that we do not wish to limit ourselves to the precise details set forth, but consider ourselves at liberty to make such slight 80 changes and alterations as fairly fall within the spirit and scope of our invention.

Having fully described our invention, what we claim as new, and desire to secure by Letters Patent, is—

1. In a sheet or page turner, the combination with a support, arms pivotally connected to said support and springs for throwing said arms from right to left, of a sliding bolt on said support to hold the arms in their ex- 90 treme right-hand position, means for operating said bolt step by step to separately re- 95 lease the arms, and means in position to be engaged by said arms when they are returned to their right-hand position for automatically releasing the bolt to permit the same to engage said arms.

2. In a leaf or page turner, the combination with arms adapted to be connected with the pages or leaves of a book or sheet of music 100 and springs for forcing said arms from right to left, of a spring-pressed bolt normally dis- 105 posed in the path of said arms, ratchet-teeth on said bolt, a push-rod, a spring-pressed dog on said rod to engage said ratchet-teeth and move the bolt step by step out of the path of the arms, another spring-pressed dog adapted to prevent upward movement of the bolt, a lever in rear of the arms when they are in their right-hand position and adapted to be oper- 110 ated thereby, and a plate on said lever adapt- 115 ed to engage both of said dogs and force them out of engagement with the bolt.

3. In a page or leaf turner, the combination with a support and means thereon for turn- 115 ing the pages of a book or sheet of music, of plates connected to said support, spaced apart and having oval openings therein, and a rod adapted to be inserted in the binding of a book and having recessed portions for inser- 120 tion in said oval openings in the plates.

In testimony whereof we have signed this specification in the presence of two subscribing witnesses.

JOHN B. WILLIAMSON.
HARRY L. MEANS.
